UNITED STATES PATENT OFFICE.

WILLIAM F. HUDSON, OF PHILADELPHIA, PENNSYLVANIA, ASSIGNOR TO HUDSON MOTOR SPECIALTIES COMPANY, OF PHILADELPHIA, PENNSYLVANIA, A CORPORATION OF PENNSYLVANIA.

MUFFLER ATTACHMENT FOR MOTOR-VEHICLES.

1,336,354.

Specification of Letters Patent.

Patented Apr. 6, 1920.

Application filed November 4, 1919. Serial No. 335,785.

To all whom it may concern:

Be it known that I, WILLIAM F. HUDSON, a citizen of the United States, residing at the city of Philadelphia, in the county of 5 Philadelphia and State of Pennsylvania, have invented a certain new and useful Muffler Attachment for Motor-Vehicles, of which the following is a specification.

The leading object of the present invention is to provide an attachment for the muffler of a popular type of motor-vehicle, which is of simple, inexpensive and efficient structure and which may be secured to the muffler by means of muffler fastening parts 10 so that bolts, clamps, screws or like mediums are not required to accompany such attachment when sold.

The invention consists of the improvements hereinafter described and finally 20 claimed.

The nature, characteristic features and scope of the invention will be more fully understood from the following description taken in connection with the accompanying 25 drawings forming part hereof, and in which:—

Figure 1, is a perspective view of the attachment embodying features of the invention.

30 Fig. 2 is a fragmentary view, in side elevation, of a muffler equipped with the attachment, and

Fig. 3, is a view in cross-section, taken upon the line 3—3 of Fig. 2.

35 For the purpose of illustrating my invention I have shown in the accompanying drawings one form thereof which is at present preferred by me, since the same has been found in practice to give satisfactory 40 and reliable results, although it is to be understood that the various instrumentalities of which my invention consists can be variously arranged and organized and that my invention is not limited to the precise 45 arrangement and organization of the instrumentalities as herein shown and described.

The muffler of a popular make of motor-vehicle, as now constructed, is provided at 50 its rear with a removable cap from which projects rearwardly a short section of tubing of substantially elliptical cross-section forming a vent for the exhaust gases from the vehicle motor. The said cap is main-

tained in place by means of a nut having 55 screw-threaded relation with a rod extended from the muffler. The attachment of the present invention is designed to co-operatively engage over said vent and to be maintained in proper position by means of the 60 nut just referred to. The attachment comprises a body portion 10, which is of inverted scoop-like formation, provided at its inner end with an extension 11. The forwardly extending body is disposed at an 65 inclination with respect to said extension. The extension is provided, laterally considered, with a pair of resilient, muffler-vent engaging members 12. These members are downwardly and inwardly bent as clearly 70 illustrated in Fig. 3. The extension 11 is provided with a neck 13 which terminates in an attachment plate 14 apertured as at 15. The plate 14 is disposed substantially 75 at right angles to extension 11.

To attach the device of the invention to a muffler the nut 16 and washer 16' of the muffler are removed, the members 12 caused to engage over the muffler vent 17 and the aperture 15 of plate 14 passed over the 80 muffler rod 18 so that plate 14 abuts against the muffler cap 19. Nut 16 and washer 16' are replaced. Thus the muffler attachment 85 is secured against end-wise movement by nut 16 and prevented from movement around the muffler by the members 12 which engage the muffler vent.

The above described attachment serves to deflect the engine exhaust, passing through the muffler, in a direction toward the ground. It is customary to carry at the rear of a motor-vehicle a spare tire a portion of which is in line with the muffled vent. By the employment of the attachment above described 90 the scoop-like body thereof affords efficient protection against heat, oily soot and the like impinging against such spare tire the advantage of which is readily apparent.

It will now be apparent that I have devised a novel and useful construction which embodies the features of advantage enumerated as desirable in the statement of the invention and the above description and while I have in the present instance shown and described the preferred embodiment 100 thereof which has been found in practice to give satisfactory and reliable results, it is to be understood that the same is suscep-

tible of modification in various particulars without departing from the spirit or scope of the invention or sacrificing any of its advantages.

5 What I claim is:

1. In combination a muffler for motor-
10 vehicles, a cap provided with a rear-
wardly projected vent of substantially el-
liptical cross-section detachably secured to
said muffler, a device having a part shaped
15 for coöperatively engaging over said vent
and for abutting against said cap and hav-
ing a part serving to deflect the exhaust
gases passing from said vent in a direction
toward the ground and means common to

said cap and device for securing same with
respect to said muffler, said means being
the sole method of attachment.

2. A device of the character stated com-
prising a scoop-shaped body having an ex-
10 tension disposed at an angle thereto said
extension being provided with resilient,
muffler-vent engaging members and a plate
projected from said extension at substan-
tially right-angles thereto said plate being 20
apertured for passage over a muffler rod to
provide a means of attachment.

In witness whereof, I have hereunto
signed my name.

WILLIAM F. HUDSON.
